E. W. HOWELL,
REFRIGERATING APPARATUS,
APPLICATION FILED APR. 17, 1915.

Patented Sept. 12, 1916.

2 SHEETS-SHEET 2.

UNITED STATES PATENT OFFICE.

EDWARD W. HOWELL, OF NEW YORK, N. Y., ASSIGNOR TO W. DEAN SMITH, OF BROOKLYN, NEW YORK.

REFRIGERATING APPARATUS.

1,198,352.

Specification of Letters Patent. Patented Sept. 12, 1916.

Application filed April 17, 1915. Serial No. 22,134.

To all whom it may concern:

Be it known that I, EDWARD W. HOWELL, a citizen of the United States, residing at Astoria, in the borough of Queens, city of 5 New York, county of Queens, and State of New York, have invented certain new and useful Improvements in Refrigerating Apparatus, of which the following is a specification.

10 My invention relates to refrigerating apparatus of the still and absorber type, and it has for its object to improve apparatus of this kind and provide for the automatic operation thereof, as will be described and 15 pointed out in the following specification. One great difficulty experienced in operating with known types of automatic refrigerating apparatus has been that the back pressure in the absorber and the refrigerating coil has been sufficient to interfere with and often prevent free movement of 20 the ammonia in the several stages of its flow.

The present invention has for one of its 25 objects to overcome this difficulty.

The invention has been devised with especial reference to simplifying and making compact the apparatus, thereby adapting it for use in dwellings, hotels, restaurants, 30 clubs, etc., where comparatively small refrigerating units are required. The apparatus, as will be pointed out, is adapted to effectively accomplish the steps of vaporizing or distilling, condensing, expanding, 35 and freely absorbing, ammoniacal vapors for refrigerating purposes.

I have illustrated in the accompanying drawings the preferred form of my invention, without, however, intending thereby 40 to limit the invention in its practical applications to all of the details of construction and arrangement which appear in the said drawings.

In the accompanying drawings Figure 1 45 is a side elevation of refrigerating apparatus embodying my improvements, parts being illustrated in section. Fig. 2 is a transverse sectional view of the apparatus. Fig. 3 is a detail view, partly in section, 50 and largely diagrammatic in character, of the automatic valves employed in the apparatus. Fig. 4 is a detail view illustrating the connection through which the expansion valve is operated. Fig. 5 is an end view of

the controlling valve 30 showing some of 55 the pipes or conduits connected therewith.

Referring to the drawings, 2 represents the still and absorber of the apparatus. It is in the form of a tight metal cylinder resting upon suitable supports, 3.

4 indicates the receiver for the liquefied ammonia. It is preferably located, for compactness and convenience of arrangement, directly below the retort 2 and is supported within a water-containing vessel 5 that constitutes the condenser of the system. Means are provided for heating the still, and I have illustrated for that purpose a gas burner 6 located longitudinally of and directly below the cylindrical still. A line of 65 piping, 7, for conveying away the ammoniacal vapors, connects with the upper portion of the still and leads to the receiver 4. In this line of piping is located a pressure gage 8 and a check valve 9. A water supply pipe 75 10 leads to the water container 5 of the condenser, and another pipe 11 leads therefrom for conveying away the water after it has served its purpose in condensing. A pipe or conduit 12 leads from the lower part of 80 the receiver 4 to the expansion coil 13, and other piping or vapor conduit, 14, connects the expansion coil with the still-absorber, entering the latter in its lower part and preferably directly over the burner 6. The 85 portion of the piping 14 that is within the still-absorber tank extends through it for practically its entire length, and is indicated by the character 15, it being perforated to permit the ready escape of the vapors or gases being delivered into the tank 90 2 where they are reabsorbed by the water contained therein. A check valve 16 is located in the line of piping 14 and prevents back pressure from the still-absorber 95 affecting the flow of vapor through the system.

The parts of the apparatus thus far described are of general and well known construction and operation, and may be varied 100 widely in detail without affecting my present invention. The drawings illustrating these parts of the system are largely dia-grammatic.

Within the tank 2 constituting the still 105 and absorber is mounted a diaphragm 17, that extends from end to end of the tank and is, in the main, of the same shape as

the latter, being, in the construction shown in the drawings cylindrical and concentric with the shell of the tank throughout a greater portion of its circumference. The 5 lower portion of the diaphragm, that part that is directly opposite the portion of the shell of the tank that is heated from the burner 6 is cut away, and wings 19 connect the edges formed by thus cutting away the 10 diaphragm with the shell of the tank 2. The upper portion of the diaphragm is perforated, as at 18, and the wings also, as indicated at 20. Circulation spaces are formed between the wall of the tank and the 15 diaphragm, as indicated at 21, 21. This construction of still-absorber has been found to be very efficient in refrigerating apparatus of the type herein presented. When the aqueous contents of the still, which should 20 fill it to within four or five inches of its top, have been charged with ammonia, and the time has come to drive off the ammonia vapor, the burner 6 is lighted, and the valve 9 in pipe 7 opens. Hot ammonia vapor now 25 passes off from the still and collects in the receiver 4 where it is condensed into liquid form by the body of cold water in which the receiver is immersed. During this process of distillation the inner diaphragm 17 pro- 30 motes an active circulation of the contents of the still. The liquid within the diaphragm is heated directly from the burner and rises, passing out through the apertures 18 into the spaces 21, through which it flows 35 in a downward direction and again enters the space within the diaphragm, passing through the apertures 20 in the wings 19 thereof, where it is again heated. The circulation becomes active and this cycle of flow 40 is repeated again and again, so that the entire contents of the still are repeatedly heated until all the ammonia vapor that it is practical to remove has been separated from the water within the still and has passed off 45 through the pipe 7 to the condenser. The most important function of the diaphragm, however, is manifest during the absorption period of operation, when the ammonia gas, having passed through the expansion coils 50 18 reenters the still-absorber through the pipe 15, escaping in the form of small particles or bubbles. The ammonia gas thus broken up is absorbed by the water contained within the tank 2 very actively, and, 55 as is well known, with the production of considerable heat. Unless means are provided for removing or dissipating this heat as it is generated, the contents of the still will soon become so hot that sufficient pressure will be generated to prevent further admission of the gas, thus interrupting the process and destroying the efficiency of the apparatus. By constructing the still-absorber as described, that is, with the internal diaphragm 17, and introducing the

pipe, through which the ammonia gas is discharged into the lower part of the space inclosed by the diaphragm, an active circulation within the tank is quickly set up, the hot liquor charged with ammonia vapor 70 in the lower part of the tank and within the diaphragm, rising and finally escaping through the perforations 18, whence it passes downward through the spaces 21, and thence through the perforations 20 in the dia- 75 phragm wings back into proximity to the pipe 15 to be again and further charged with ammonia. The liquid in passing through the spaces 21 flows, in comparatively thin sheets, in direct contact with the 80 outer walls of the tank, thus insuring direct and rapid radiation of heat.

I will now describe the means which I have devised for making the operation of the apparatus automatic. 22 is the expansion 85 valve, located in the line of piping 12 connecting the receiver 4 and the expansion coils 13. It operates to cut off communication between these two parts of the apparatus during the distillation period, but 90 during the rest of the time of operation it is open, either continuously or intermittently. I have shown means for causing it to be intermittently opened and closed, allowing a flow of the ammonia from tank 95 4 to the expansion coils for a certain period of time, and then cutting off the flow and permitting the expansion of the ammonia, with resulting cooling effects, this being the preferred manner of operation. The automatic means are controlled and operated by water, caused to flow into and from a vessel 23 in which is located a float 24. The float is connected by a link 25 with an arm 26 extending from the stem 27 of the valve 22. 100 Water is supplied to the vessel 23 through a pipe 28, and is discharged through a siphon 29.

The relationship of the parts just described is preferably such that it takes approximately a half hour for the vessel to fill, while the discharge is very much more rapid. The float has a loose connection, and one that is also preferably adjustable, with the valve, and, in the arrangement shown, 110 115 does not begin to open the expansion valve until the vessel is approximately half filled. There will thus be periods of approximately fifteen minutes each during which the expansion valve is open, alternating with other periods of approximately the same duration during which it is closed.

Supposing now the parts to be in the position indicated in Fig. 3, that is to say, the float 24 in the lower part of the vessel 23 and the valve 22 closed, and that water begins to enter the tank through the pipe 28. As the vessel fills the float rises gradually, the valve beginning to open at about the time it is half filled and remaining open 120 125 130

until the water level reaches such point as to start the siphon 29, whereupon the vessel is rapidly emptied and the float falls, closing the valve, which remains closed until again 5 opened by the float, on the cycle of movements described being repeated.

It is apparent that the length of this cycle of operations may be varied at will, as by changing the size of the vessel 23, or of the 10 water supply thereto. The length of time the expansion valve remains open as compared with the time it is closed may also be varied by adjusting the connection between the float and the stem of the valve, the arm 15 26 being represented in Fig. 4 as adjustable relative to the float 24, for this purpose.

It will be understood that the operations of the expansion valve and of the heater 6 are carried on alternately, and I have devised and herein shown automatically operating mechanism for controlling the operations of these two parts of the apparatus. This preferably consists of a valve arrangement, designated as a whole by 30, arranged 25 to be controlled by a float 31 located in a water vessel 32. This vessel is supplied with water through a pipe 33 and is emptied through a siphon 34. The supply pipe 33 is connected with the main water supply 30 pipe 35 with which it has constant communication. The pipe 35 also serves to supply the pipe 10, through which water passes to the vessel 5, where it serves to condense the ammonia vapors driven off during the distillation period,—as well as the pipe 28 that supplies the water vessel 23. The valve arrangement 30 is, however, interposed between the supply pipe 35 and the pipes 10 and 28, so that the latter are supplied only 40 when the valve is in proper position. The branch pipe connections between the pipe 35 and the valve 30 are designated respectively 10' and 28'. The valve 30 is compound in its nature and it consists of a casing 36 preferably of cylindrical form, and a plug 37 rotatable therein. The plug is mounted upon or secured to a stem 38 to which is secured an arm 39 that is connected by a link 40 with the float 31. There are several 45 ducts or channels through the plug of the valve. One of these, 41, is adapted to establish communication between the supply pipes 28 and 28', leading from the main water supply pipe 35 to the vessel 23, when 50 the valve is adjusted to proper position, the said supply pipes being connected to the casing of the valve 30 and communicating with apertures therein that register respectively with the ends of the channel 41. Another channel 42 through the valve plug is arranged to put into communication the water pipes 10, 10' by which the condenser is supplied with water for keeping it cool.

The third channel through the plug of the 60 valve, 43, is adapted to put into communica-

tion two pipes, 44 and 45, that connect with the casing of the valve, the former of these pipes, 44, being the main gas supply pipe, and the latter, 45, the supply pipe leading from the valve, 30, to the burner 6. The 70 channels in the valve plug are so disposed that the water channel 42 and the gas channel 43 simultaneously register with and unite the sections of pipe with which they coöperate, so that water is supplied to the 75 vessel surrounding the condenser and receiving tank 4, and gas is supplied to the burner 6, when the valve is in one position, this being the position assumed during the distillation period of operation, the channel 80 41 then occupying a position out of register with the pipes 28 and 28', communication between which is thus cut off so that the vessel 23 is not supplied with water during this period. When the period of expansion 85 and absorption arrives the valve is adjusted to a position in which the channel 41 unites the water supply pipes 28 and 28', while the channels 42 and 43 are out of register with the pipes they are adapted respectively 90 to unite, so that the gas is cut off from the burner 6 and the flow of water through the vessel 5 is discontinued.

The size of the vessel 32 and the volume of water per unit of time delivered through the 95 supply pipe 33 are so related that the vessel 32 is filled and emptied once in every twenty-four hours, the emptying being rapid and taking only a negligible period of time.

The float 31, like the float 24, has a lost motion connection with the valve that it controls, and the connections are so adjusted in an apparatus arranged as is that herein being described, that the valve occupies a position with the channel 41 uniting the pipes that supply the vessel 23 with water during twenty-two hours, and, the float 31 then coming into operation and shifting the valve plug, the channels 42 and 43 are brought 100 into register with the pipes they unite, so that water is supplied to the vessel 5 and gas to the burner 2 for two hours of the twenty-four.

In order that the supply of water to the 115 vessel 32 may be regulated, I provide the supply pipe 33 with a reducing valve 46.

The operation of the apparatus may now be described, it being assumed that the distillation period has just been completed and 120 the available ammonia employed in the system has been condensed and is in the receiver 4 in liquid form, and that the water vessel 32 has just been emptied, allowing the float 31 to fall. This movement of the 125 float causes the valve 30 to be moved to a position to shut off the supply of gas to the burner, and the supply of water to the condenser, and simultaneously turns the water into the vessel 23 which thereupon takes up 130

its work of operating and controlling the expansion valve. The intermittent action of this valve, which is continued, in the apparatus described, for twenty-two hours, operates to admit charges of ammonia to the refrigerating coil where it expands into gas and exerts a refrigerating action, the gas passing from the refrigerating coils back to the tank 2 where it is absorbed by the water contained therein. After this operation has continued for the desired length of time, twenty-two hours in the instance supposed, the vessel 32 becomes filled to an extent sufficient to cause operation of the valve 30, so that the flow of water that is employed to operate the expansion valve is cut off, and connections are established so that gas is supplied to the burner 6 and water to the cooling vessel 5 of the condenser. The burner operates to heat the contents of the still which causes the ammonia gas that has been absorbed by the water contained in the tank 2, to be distilled in the usual way. This cycle of operations is repeated again and again and it is entirely automatic.

What I claim is:—

1. In a refrigerating apparatus, a still and absorber, consisting of a tank for the ammoniacal liquor, in which is located a diaphragm extending from end to end of the tank, substantially parallel with the shell thereof, cut away in its lower portion and having wings that unite the edges formed by the said cut away part with the shell of the tank, and perforated in its upper and its lower parts to permit and facilitate circulation, and a burner arranged to apply heat externally to the shell of the tank directly below the cut away part of the diaphragm and between the said wings thereof.
2. In a refrigerating apparatus, a still and absorber, consisting of a tank for the ammoniacal liquor, in which is located a diaphragm extending from end to end of the tank and substantially parallel with the shell thereof, the lower portion of the diaphragm being cut away and the upper portion thereof perforated to permit circulation of the liquor from the space inclosed by the diaphragm to the space between it and the shell of the tank, a heater arranged to apply heat externally to the shell of the tank directly below the said cut away part of the diaphragm, and a perforated return pipe for delivering the ammonia gas to be reabsorbed, located within the tank between the edges formed by the cut away part of the diaphragm.
3. In refrigerating apparatus of the still and absorber type, comprising a valve controlling the flow of the volatile liquid to the expansion chambers of the system, automatically operated means for intermittently opening and closing the said valve during the refrigerating period of the operation of

the apparatus, and means for regulating and controlling the periodicity of such movements.

4. In refrigerating apparatus of the still and absorber type, comprising a valve controlling the flow of the volatile liquid to the expansion chambers of the system, hydraulically operated automatic means for intermittently opening and closing the said valve during the refrigerating period of the operation of the apparatus.

5. In refrigerating apparatus in which the refrigerating effects are secured by the expansion of a volatile liquid, the combination with a container for the liquid, an expansion coil, and a conduit between these two, of an expansion valve in said conduit, a float connected with and arranged to operate the said valve, a liquid-containing vessel in which the float is arranged, and means for regularly filling and emptying the said vessel whereby the float is caused to operate the expansion valve intermittently.

6. In an automatic refrigerating apparatus in which the refrigerating effects are secured by the expansion of a volatile liquid, the combination with a vessel serving alternately as a still and as an absorber, a condenser and collector for the refrigerating liquid, an expansion coil, and circulating pipes connecting these elements in series, of an automatic valve arranged to permit the flow of the refrigerating liquid from the collector therefor to the expansion coil, arranged to open and close at regular intervals of time during the refrigerating period of operation of the apparatus.

7. In refrigerating apparatus of the still and absorber type, an expansion valve, and means for causing the opening and closing of the valve arranged to operate the valve intermittently during the period of refrigeration, the periods of operation being relatively short, and other intermittently operating means arranged to control the operation of the means that work the expansion valve, the period of operation of the last said intermittently operating means being of relatively long duration.

8. In an automatic refrigerating apparatus of the still and absorber type, the combination with a still and absorber, a condenser and collector for the liquefied refrigerating agent, and an expansion coil, these parts being connected in series, of an automatic intermittently operating valve for controlling flow to the expansion coil during the period of refrigeration, and automatic means for cutting out the operation of the said valve, leaving it in condition to prevent flow to the refrigerating coil, at the end of the refrigerating period, and for restoring it to operation at the end of the distillation period, the said means being time-controlled in operation.

9. In automatic refrigerating apparatus of the still and absorber type, the combination of a liquid container arranged to serve alternately for the distillation and 20 the absorption of the refrigerating agent, a container and collector for the liquefied refrigerating agent, an expansion coil and connecting conduits uniting these parts in series, of a burner for heating the said liquid 25 container, means for supplying fuel to the burner, a water circulating system for the condenser, an expansion valve, means for operating the valve operated by a flow of liquid, a valve for controlling the supply of 30 fuel to the burner, the supply of water for condensing purposes, and the supply of water for operating the expansion valve, such valve being arranged to insure the supply of fuel and the water for condensation 35
- simultaneously but alternately with the liquid supply that operates the expansion valve, and means for operating the said controlling valve intermittently.
10. In refrigerating apparatus in which the refrigerating effects are secured by the 25 expansion of a volatile liquid, the combination with a container for the said liquid, an expansion coil and a conduit between these two, of an expansion valve in the said conduit, and means for operating the valve 30 automatically, arranged to alternately open and close it during uniform, relatively short, periods of time while refrigerating operation is taking place.
